VEHICLE ROOF

Frank W. Derenski, 11009 Morrison St.,
North Hollywood, Calif. 91601

Filed Dec. 16, 1968, Ser. No. 15,003

Term of patent 14 years

Int. Cl. D12—14

U.S. Cl. D14—27

The automobile shown in broken lines in FIGURE 1 is included for illustrative purposes only.

I claim:

The ornamental design for a vehicle roof, as shown and described.
